CENTRIFUGAL PUMPING SYSTEM

Filed Dec. 21, 1928

UNITED STATES PATENT OFFICE

THOMAS F. MOORE, OF MORRIS PLAINS, NEW JERSEY

CENTRIFUGAL PUMPING SYSTEM

Application filed December 21, 1928. Serial No. 327,575.

This invention relates to hydraulic pumping apparatus involving the use of a centrifugal pump for removing water from marshes, sink-holes and other repositories in 5 the soil as may be required in preparing the soil for the reception of sewers, water mains and other conduits or in the construction of the foundations of buildings and other super-structures.

10 This pump may be located in any operative position most suitable or convenient for the work to be performed and its intake and delivery sides connected to suitable conduits leading respectively to the source of supply 15 and to the place of discharge either of which may be above or below the level of the pump and at widely varying distances therefrom.

It frequently happens that the water passing through the pump is laden with more or 20 less sand, silt and other foreign matter, portions of which are sometimes drawn or forced into the glands for the impeller shaft of the pump thereby cutting, scoring or otherwise impairing both the shaft and glands to such 25 an extent as to allow air to enter the pump through the impaired glands and thus reduce the working efficiency of the pump.

Various methods have heretofore been proposed for preventing the entrance of air to 30 the interior of the pump through the glands or stuffing boxes for the shaft bearings such, for example, as connecting the interior of the outer part of the pump case to both of the glands to conduct a part of the water to 35 the glands for sealing the same against the entrance of air.

This method has a certain degree of efficiency when the pump is working under a large supply or full head of clean water but 40 has proven to be inefficient for sealing the bearing glands against the entrance of air when the water supply is relatively small and laden with more or less sand and other foreign matter for the reason that the grit 45 soon destroys the glands and permits the leakage of air therethrough.

Another method is the use of grease cups for forcing grease into the glands for lubricating and sealing purposes, but this method 50 requires almost constant attention and is,

therefore, impracticable in apparatus of this character.

A further method heretofore proposed for use on large dredging pumps is to provide an extra force pump for forcing clean water into the bearing glands which, of course, would be prohibitive in connection with the present apparatus by reason of the added costs and necessity for a separate source of supply of clean water.

The main object of this invention is to provide means whereby a portion of the water passing through the pump is automatically clarified, so far as any injurious grit content is concerned, and the clear water diverted to 65 the stuffing boxes or bearing glands of the impeller shaft under pressure to seal said glands against the entrance of air therethrough into the pump.

In other words, I have sought to divert 70 clarified portions of the pumped water to the stuffing boxes under pressure sufficient to expel the air therefrom and to prevent the filtering of air therethrough into the pump irrespective of the amount of water passing 75 through the pump.

Other objects and uses relating to specific parts of the apparatus will be brought out in the following description.

In the drawings:

Figure 1 is a side elevation of a portion of a centrifugal pumping apparatus embodying the various features of my invention.

Figure 2 is an end elevation, partly broken away, of the same apparatus, viewed from 85 the intake side of the pump.

Figure 3 is a horizontal detail sectional view through the upper portion of the stand pipe, taken in the plane of line 3-3, Figure 1.

Figure 4 is an enlarged sectional view of 90 one of the bearings for the impeller shaft of the pump and adjacent end of one of the water supply pipes for maintaining a water seal in the stuffing box of the bearing.

The invention is adapted to be used in connection with a centrifugal pump —1— having suitable intake and outlet conduits —2— and —3—, said pump being provided with the usual impeller shaft —4— and bearing

glands or stuffing boxes —5— therefor in opposite ends of the pump case.

The outlet conduit preferably includes a pipe T-section —6—, a check valve —7— and a throttle valve —8—, all of which are arranged in sequence from the delivery side of the pump and preferably in more or less close proximity to each other and to the pump. A stand pipe —9— of relatively large capacity is secured to the upper side of the T-section —6— to communicate with the interior thereof and extends upwardly some distance above the top of the pump —1— for receiving a portion of the water or other pumped liquid delivered through the outlet conduit —3—.

The extreme upper end of the pipe —9— is provided with an air vent —10— to allow free rise and fall of the liquid in the stand pipe, said vent pipe being provided with a try-cock —10'— to enable the operator to determine the presence or absence of air in the stand pipe and also whether or not the valve —8— is closed sufficiently to cause the water to rise in the stand pipe with enough pressure to be delivered to the stuffing boxes.

A pair of relatively small branch pipes —11— lead from the upper end of the stand pipe —9— to the glands or stuffing boxes —5— for supplying a part of the pumped water to the glands for sealing the same against the entrance of air therethrough to the interior of the pump which would materially reduce the efficiency of the pump.

The object of the stand pipe —9— of relatively large capacity as compared with the size of the pipes —11— is to permit part of the pumped water delivered through the outlet conduit to rise more or less slowly therein so as to allow any sand, silt or other foreign matter which may be carried into the stand pipe to settle into the main outlet conduit and to be carried therethrough by the force of the pump thereby maintaining a greater or less quantity of substantially clear water in the upper portion of the stand pipe to be conducted therefrom to the gland bearings through the conduits 11.

The rise of the pumped water in the stand pipe —9— may be facilitated and closely regulated by proper adjustment of the throttle valve —8— which, when adjusted, more or less toward its closed position, serves to choke the outflow of water through the conduit —3— sufficient to cause a part of the water to slowly back up into the stand pipe —9— until it reaches the level of the adjacent ends of the branch pipes —11—.

That is, the throttle valve —8— serves as a means for causing a part of the pumped water to rise in the stand pipe —9— to or slightly above the level of the adjacent ends of the branch pipes —11— at a rate of speed sufficiently slow to allow sand, silt and other solid matter which may be carried into the stand pipe to gradually precipitate into the

discharge conduit —3— where it is carried off with the water discharged through said conduit to the place of delivery.

Under these conditions the water in the upper portion of the stand pipe will be practically clear or free from sand and other sediment which might be injurious to the bearings of the impeller shaft of the pump.

This clear liquid is automatically delivered through the pipes —11— to the pump bearings —5— under sufficient pressure to force the air from the interior thereof outwardly through all portions thereof and thereby to effectively seal said bearings against the entrance of air, while at the same time flowing in part through any clearances that may be present between the shaft and gland.

The stand pipe —9— may be of any desired height sufficient to carry the water level therein some distance above the level of the glands —5— to give the necessary pressure of the clear water passing through the pipes —11— to said glands for expelling the air from said glands and sealing the same against the entrance of air in addition to the other function of the stand pipe in allowing the sediment therein to automatically precipitate to the bottom thereof and thereby assuring the delivery of substantially clear water to the glands —5— through the pipes —11—.

Suitable means is also provided for supplying clear water from a separate source when desired and for this purpose a supply pipe —12— leading from any source of clear water supply is connected to the upper end of the stand pipe at about the level of the upper ends of the delivery pipes —11— in which case the portion of the stand pipe immediately below the supply pipe —12— and upper ends of the delivery pipes —11— will be provided with a valve —13— capable of being closed at will when the clear sealing water or other liquid is introduced into the glands —5— through the pipes —11— under sufficient pressure to expel air from said glands and seal the same against the passage of air therethrough, it being understood that the extra supply pipe —12— may be provided with a valve, not shown, for controlling the passage of water therethrough.

That is, when water is supplied to the glands through the extra pipe —12— the valve —13— will be closed to prevent the passage of such water into the discharge conduit —3—.

On the other hand, under the normal operation of the pump the water supply through the pipe —12— will be cut off and the valve —13— will be opened and by properly adjusting the valve —8— in the outlet pipe —3— the water discharged from the pump through said conduit will be caused to rise slowly in the stand pipe —9— thereby allowing any sand, silt or other foreign mat-

ter to precipitate in the conduit —3— to be carried off with the main outflow of the water.

This leaves the upper portion of the column of water in the stand pipe —9— substantially free from solids and as soon as it rises to the level of the upper ends of the pipes —11— it will overflow therethrough to the glands —5— under sufficient head or pressure to expel the air from said glands and also effectively seal the same against the entrance of air therethrough.

It is now evident that the stand pipe —9— serves as a settling basin for the water therein in which the solid matter is precipitated to the bottom thereby leaving the clear water at the top for supplying the necessary water seal to the glands of the impeller shaft.

The check valve —7— is merely to prevent the backflow of water and air through the conduit —3— into the pump while permitting the free outflow of water and air from the pump.

The operation will now be readily understood from the foregoing description and the accompanying drawings and while I have shown a specific means for carrying out the various objects of the invention it is evident that certain changes may be made in the detail construction without departing from the spirit of the invention.

What I claim is:

1. The combination with a centrifugal pump having an inlet conduit and an outlet conduit and glands for the impeller shaft of the pump, a stand pipe connected to the outlet conduit for receiving pumped water from the outlet conduit, means for causing a portion of the pumped water to rise in the stand pipe, and means for conducting the water from said stand pipe to the glands for sealing said glands against the passage of air therethrough.

2. The combination with a centrifugal pump having an inlet conduit and an outlet conduit and glands for the impeller shaft of the pump, a throttle valve in the outlet conduit, a stand pipe connected to the outlet conduit between the valve and pump and extending some distance above the level of said glands, said valve being adjustable at will to vary the volume of water passing therethrough and thereby to cause the water to rise to a predetermined level in the stand pipe, and branch pipes leading from the water level in the stand pipe to said glands for sealing the same against the passage of air therethrough.

3. The combination with a centrifugal pump having an inlet conduit and an outlet conduit and a gland for the impeller shaft of the pump, a stand pipe connected to the upper side of the outlet conduit and extending upwardly some distance above the level of the pump for receiving portions of the

pumped liquid passing into said conduit, means for restricting the outflow of water through the outlet conduit for causing portions of said water to rise in the stand pipe to a predetermined level above said gland, and means for conducting the water from said predetermined level in the stand pipe to said gland.

4. The combination with a centrifugal pump having an inlet conduit and an outlet conduit and a gland for the impeller shaft of the pump, a stand pipe connected to the outlet conduit for receiving a part of the liquid passing through the outlet conduit, a valve in said pipe adapted to be opened and closed at will, means operable at will for restricting the outflow of the water through the outlet conduit beyond the stand pipe and causing a portion of the water to rise to a predetermined level in the stand pipe and a branch pipe leading from the stand pipe to said gland for supplying water thereto and sealing the same against the passage of air through the gland.

5. The combination with a centrifugal pump having an inlet conduit and an outlet conduit and glands for the impeller shaft of the pump, a stand pipe connected to the outlet conduit and extending upwardly some distance above the top of the pump, branch pipes leading from the upper end of the stand pipe to said glands, means operable at will for restricting the flow of the pumped water through the outlet conduit beyond the stand pipe sufficiently to cause a portion of said water to rise in the stand pipe to the level of the connections of the branch pipes therewith.

In witness whereof I have hereunto set my hand this 14th day of December, 1928.
